CLAIM

The ornamental design for a vaporizer device with cartridges, as shown and described.

DESCRIPTION

FIG. 1 is a top, rear, and right side perspective view of a vaporizer device with cartridge showing a first embodiment of our design;

FIG. 2 is a top view thereof;

FIG. 3 is a left view thereof;

FIG. 4 is a rear view thereof;

FIG. 5 is right side view thereof;

FIG. 6 is a front view thereof; and

FIG. 7 is a bottom view thereof.

FIG. 8 is a top, rear, and right side perspective view of a vaporizer device with cartridge showing a second embodiment of our design;

FIG. 9 is a top view thereof;

FIG. 10 is a left view thereof;

FIG. 11 is a rear view thereof;

FIG. 12 is right side view thereof;

FIG. 13 is a front view thereof; and

FIG. 14 is a bottom view thereof.

FIG. 15 is a top, rear, and right side perspective view of a vaporizer device with cartridge showing a third embodiment of our design;

FIG. 16 is a top view thereof;

FIG. 17 is a left view thereof;

FIG. 18 is a rear view thereof;

FIG. 19 is right side view thereof;

FIG. 20 is a front view thereof; and,
